UNITED STATES PATENT OFFICE.

JAMES BOYD MARTIN AND JOHN VAIL MARTIN, OF NEW YORK, N. Y.

PLUMBER'S FURNACE.

1,356,960.

Specification of Letters Patent. Patented Oct. 26, 1920.

Application filed February 11, 1920. Serial No. 357,929.

To all whom it may concern:

Be it known that we, JAMES BOYD MARTIN and JOHN VAIL MARTIN, citizens of the United States, and residents of New York city, in the county of Kings and State of New York, have invented certain new and useful Improvements in Plumbers' Furnaces, of which the following is a specification.

Our invention relates to stoves, and particularly to small portable furnaces.

In the course of their daily work, the members of certain trades, such as plumbers, tinsmiths, roofers, electrical workers, and the like, customarily employ small furnaces for melting various substances, or for heating tools and materials. The furnaces in general use, while sufficiently compact to permit them to be carried to and from the work, include a reservoir for a substantial quantity of fuel, such as gasoline or kerosene, a burner therefor, and a superstructure for supporting the tools or materials. The reservoir and burner are necessarily somewhat heavy, and when the former is filled with fuel, furnaces of this type are a considerable burden, especially when heavy tools are also carried.

Workers of such trades, however, also customarily include as part of their equipment a portable torch, sometimes called a blow-torch, a great many forms being well known. The common type of torch, however, includes a nozzle from which the flame is laterally projected. These torches hold fuel enough to permit them to burn for a considerable length of time.

An object of our invention is to eliminate the heavy reservoir and burner of the usual furnace, and to construct the furnace which, while retaining the requisite strength and rigidity, is relatively light, being adapted to use the flame of an ordinary blow-torch for heating purposes, thus preventing the duplication of heating elements in the usual outfit carried by such mechanics.

A further object is to construct a portable furnace of this type which is extremely strong and simple to manufacture, permitting it to be sold at a relatively low price, and facilitating the repair and renewal of the various parts thereof.

Another object is to simplify the means for supporting the melting pot or other object in line with the furnace. We also provide supporting means whereby a container

may either be held directly in the flame of the blow-torch or supported above the flame, in accordance with the degree of heat desired. In the specific form, one object of our invention is to provide a construction in which the two supports are unitary, thus greatly simplifying the construction. Specifically, we have invented a furnace in which the supporting means for holding the furnace body at suitable height, for holding a container above the flame, and for holding such container in the flame, are integral and continuous. We also have disclosed a preferred form, in which the main parts are constructed entirely of common sheet metal, and are so arranged that they may be manufactured rapidly and cheaply.

Other objects and advantages of our invention will be apparent from the following description, taken in connection with the accompanying drawings, in which:

Figure 1 is a perspective view of a furnace, showing a common type of blow-torch in position,

Fig. 2 is a vertical section through Fig. 1, indicating the position of a container supported above the flame, and

Fig. 3 is a top plan view.

The furnace includes a body portion 10 open at the top, preferably throughout its entire width, and which may be provided with a bottom 11 connected to the body portion in any desired way, as by seam 12. The body and bottom are preferably constructed of sheet metal, the specific arrangement disclosed being a common way of manufacturing cylindrical containers, permitting these portions of the furnace to be manufactured cheaply and quickly by standard machinery. The body 10 is provided with an aperture 13 in one side thereof, so located and proportioned that the flame of a suitably positioned hand-torch 14 will pass into the interior of the body portion through the aperture. The aperture 13 is preferably elongated vertically so as to accommodate flames from torches varying somewhat in height.

Suitable carrying means, such as the usual handle 15 carried by bail 16 mounted in ears 17 on the body 10, is preferably employed to facilitate the handling of the furnace, such means preferably being such as to permit tools, materials, etc., to be piled up in the body of the furnace without interfering with the handle.

Suitable supporting means is provided, preferably consisting of legs 18, which may be formed of sheet metal in strip form and attached to the body 10 in any desired way, as by bolts 19. Legs 18 may be of any desired shape, and preferably are spread apart at the bottom to provide a wide base. Legs 18 are preferably so designed that a blow-torch resting on the same flat surface 10 as the furnace will have its flame at a suitable height to enter aperture 13. It will be apparent from Fig. 1 that with this arrangement, the blow-torch flame is directed across the body 10, as flames from torches 15 of this type are projected with considerable force.

We provide means for suspending a suitable container or article to be heated within the body portion in direct line with the 20 flame, and also provide means for holding such container or article above the furnace body, at which point the heat will be considerably less. It will be apparent that this arrangement permits the melting of 25 solder and other metals requiring a high degree of heat by placing them in a container directly in the flame, and also facilitates the melting or thawing of other substances, such as paraffin, resin, insulating 30 material, etc., which would be burned if subjected to the direct heat of the flame. Furthermore, large containers, such as pails, may be placed across the top of the furnace 35 extending beyond the sides thereof, and the contents of the box heated. To accomplish these objects, we preferably extend the legs 18 upwardly above the top of body 10 to form a plurality of supports 20, the upper surfaces of which are preferably on the 40 same plane and suitably contoured to support the desired type of container or other article thereon.

For supporting a suitable container, such as the usual plumber's melting pot, within 45 the furnace body 10 in direct line with the flame, we employ a plurality of inwardly projecting lugs 21 which preferably are separate from the furnace body 10 and are mounted thereon, as by bolts 22. By suitably positioning and proportioning lugs 21, the bottom of the usual plumber's melting 50 pot, when resting on the lugs, will be close to the line of the flame from torch 14, so that such flame will spread evenly over the 55 bottom and provide approximately even heat throughout the lower part of the pot. In the preferred form, lugs 21 are formed from a reversely bent extension of supports 20, the construction disclosed having the 60 legs 18 and the connecting portion between supports 20 and lugs 21 located adjacent to opposite sides of the wall of the body 10, and preferably held in position against the wall, as by bolts 22 passing through both 65 the inner and outer leg and support exten-

sions, thus holding the parts in position and preventing rotation of the legs about bolts 19.

Legs 18 are preferably constructed from heavy strip metal, which is readily obtainable commercially and may be bent into shape rapidly and cheaply. While this construction provides a rigid support for the furnace, it will be apparent that the legs, if constructed of malleable metal, may be 75 bent outwardly to a greater or less extent, thus varying the height of the aperture 13 and permitting the user of the furnace to adjust it rapidly to blow-torches varying somewhat in height. 80

While we have described legs 18, supports 20 and lugs 21 as mounted on body 10 by bolts, it will be apparent that a great many other methods of mounting these parts may be employed. 85

It will be apparent that in the specific form disclosed, we have invented a furnace composed almost entirely of sheet metal, and requiring only five pieces of such metal to construct the furnace body, legs and container supports. Moreover, the legs and supports are so constructed that they may be readily removed, repaired or replaced in case of any injury, without requiring tools other than those available to the ordinary 95 mechanic.

The construction, furthermore, is one that will withstand the most severe usage. Moreover, the furnace is not only relatively light, especially compared with the usual furnace, 100 but it also provides a ready holder for carrying tools and materials which may be piled inside the furnace and project from the upper end thereof below handle 15.

While we have described the preferred 105 form of our invention, it will be apparent that other changes and variations may be made in the form shown, without departing from the spirit of our invention as set forth in this specification.

We claim:

1. In a portable furnace adapted to be heated by a torch, a body portion adapted to receive the flame from a torch and provided with side walls, means carried by said walls 115 for supporting an article within the body portion in the flame of said torch, legs for supporting the body portion located against the outer face of said side walls, supports integral with said legs and located above 120 the top of the body portion for supporting an article above said flame, and unitary means for mounting said means for supporting an article within the body and said legs upon the body. 125

2. In a portable furnace adapted to be heated by a torch, a body portion adapted to receive the flame from a torch, a plurality of metal strips connected to the inside of the body, an inturned lug adjacent the lower 130

- end of each strip for supporting an article in said flame, and a support at the upper end of each strip for supporting an article above said body and flame.
5. 3. In a portable furnace adapted to be heated by a torch, a body portion adapted to receive the flame from a torch, legs for supporting said body portion attached to the outside thereof, supports integral with 10 said legs located above said body portion for maintaining an article above said body portion and flame, and supports within the body portion integral with said upper supports for maintaining an article in said 15 flame.
4. In a portable furnace adapted to be heated by a torch, a body portion having an

opening for the entrance of the torch flame, a plurality of metal strips connected to the body and extending down the outside there- 20 of past its bottom to form supporting legs, extensions provided on the said strips projecting above the body to form supports for an article above the flame, and down-bent extensions provided on the strips projecting 25 from the said supports inside the body to points adjacent the flame opening and having inbent lugs formed thereon for supporting an article in the flame.

Signed at New York city, in the county of 30 Kings and State of New York, this 27th day of January, A. D. 1920.

JAMES BOYD MARTIN.
JOHN VAIL MARTIN.
